UNITED STATES PATENT OFFICE.

WILLIAM H. DUNN, OF CHICAGO, ILLINOIS, ASSIGNOR TO DUNN MANUFACTURING CO.,
OF CHICAGO, ILLINOIS, A CORPORATION OF ILLINOIS.

CLEANSING MACHINE.

Application filed February 24, 1919. Serial No. 278,906.

The invention relates to cleansing machines which may be used in cleansing various articles and utensils, and is particularly adapted for cleansing dishes, pans and other similar articles.

The invention has among its various objects the provision of an arrangement in which the cleansing fluid is set in motion and caused to circulate through various instrumentalities which direct the same towards the articles to be cleansed with a force sufficient to thoroughly cleanse them.

It is a further object of the invention to eliminate to the greatest degree the necessity of any manual labor to accomplish the above desired end, and also to provide an arrangement in which the danger of injury to the person using the device is reduced to a minimum.

20 The invention has as an additional object the provision of an arrangement whereby all of the instrumentalities forming the cleansing means may be separated from each other and removed from the fluid container or basin in which they are positioned, so that they and the basin may be thoroughly cleansed of any material which may adhere thereto.

It is an object of the invention to provide 30 a cleansing fluid basin with a drain board so that the water dripping from the dishes when removed from the basin will find its way back thereto.

The invention has these and other objects, 35 all of which will be explained in detail and more readily understood when read in connection with the accompanying drawings, in which

Fig. 1 is a longitudinal central section 40 through the fluid container and drain board;

Fig. 2 is a top plan view of the device shown in Fig. 1, portions of which are broken away for the purpose of illustration;

Fig. 3 is a side elevation of the agitator 45 and the portion to which it is secured;

Fig. 4 is an enlarged sectional view of the drive shaft and connections; and

Figs. 5 and 6 are details of a modified 50 guard which may be employed in the device. In the embodiment of the invention as illustrated in the drawings the use of an in-

tegral drain board 10 and basin or bucket 11 is contemplated. The bottom of this basin is provided with the drain opening 12 which is closed by the removable apertured device 55 13, which serves to catch any waste when the container is drained, and provides a means whereby said waste may be removed without the necessity of brushing or otherwise bringing the same to this point for its 60 removal. This feature forms the basis of another application, and will not be explained in detail herein. The drain pipe leading from this opening 12 is controlled by the valve 14. The bottom of this basin 65 is apertured to receive the plug 15 and cooperating parts, and to permit the shaft 16 to project into the basin sufficiently to engage certain portions forming part of the invention. This feature will be explained in detail hereinafter. The upper portion of the basin 11 is provided with an annular recess or depression 17 into which is placed the ring 18, the under side of which has an annular flange 19, which engages the basin. 70 The under side of this ring 18 is recessed as shown at 20 and provides a deflecting face to direct the cleansing fluid back towards the basin. To this ring 18 is suitably secured a spidered member generally designated 21, into which is placed the basket 22 forming a container for the articles to be cleansed. This basket is removable from the member 21. The member 21 is preferably formed of a plurality of radially disposed 75 curved arms 23, which follow the contour of the inside of the basin, and have their ends secured to the ring 18. These arms are spaced apart from the walls of the basin to permit the rotatable arms 24 of the agitator 80 25 to be arranged between them and the wall of the basin. These arms 23 are curved so as to cause the fluid to be directed towards the basket 22. Between these radial arms 23 is arranged any suitable material 85 26^a, such as wire netting or a slotted plate 26^b which will permit the water to circulate through it to the interior of the basket 22. This is provided for the purpose of preventing the user from accidentally placing his hand or finger between the stationary arms 23 and the rotating arms 24, and be-

coming injured when the basket is removed from between the arms of the spider 21.

In the event of the use of the slotted plate 26^b at this point as illustrated in Figs. 5 and 6, then the material forming edges of the slots will be bent to assist in directing the fluid towards the basket. This is illustrated in Figs. 5 and 6.

An arrangement or construction is contemplated whereby the blades 24 are rotatably connected to the element 21 so that the same may rotate with relation thereto, and be removable from the basin 11 with the element 21. The particular arrangement shown to accomplish this contemplates providing the rotatable agitator 25 with a recessed portion 26, which receives the squared end of the shaft 16. A stud 27 projects from the arms. This stud is passed through an aperture 28 in the element 21, the latter being held with relation thereto by the nut 29. The connection of the nut 29, stud 27 and element 21 is sufficiently loose to permit the arms 24 to rotate with relation thereto, the element 21 being held against rotation by frictional engagement of the ring 18 with the upper portion of the basin.

The plug 15 is screw threaded into the lowermost wall of the basin 11 and has an extension 30 constructed to receive the packing 31 and the packing nut 32, these all being bored to receive the shaft 16, which carries the beveled gear 33. One end of this plug 15 extends beyond the lowermost wall of the basin a sufficient distance to permit the uppermost half 34 of the gear casing to be secured thereto. This portion has a ledge 35 upon which is mounted the motor 36, the shaft of which has a pinion 37 which meshes with the gear 38 provided upon the shaft 16. The lowermost half 38 of the casing is secured in place by means of the bolts 39—39.

From the foregoing description of the construction it can be readily seen that when the shaft 16 is rotated by means of the motor 36, the agitator 25 having the arms 24 will be rotated within the basin, causing the fluid therein to be agitated and directed towards the curved arms 23 which are preferably held stationary and cause the fluid to circulate towards and into the basket 22 which contains the articles to be cleansed.

It is further evident that this basket 22 may be lifted out of the frame-work formed by the stationary arms 23 and when same is thus exposed, the user will be insured against injury by the wire fabric 26^a which it will be noted extends from one of the arms 23 to the other, and forms a guard preventing injury by the rotating blades 24. This wire fabric 26^a will in no way interfere with the circulation of the water towards the interior of the basket. In view of the fact that these arms 23 and the rotating

blades 24 are secured together, both of these elements are removable as a unit from the basin 11. Furthermore these elements are separable from each other, being removably held together by the nut 29.

It has been found that the rotating blades 24 in themselves produce an efficient means whereby the water is forced from the walls of the container towards the center thereof with sufficient force to thoroughly cleanse the articles contained in the basket, and thus the curved arms 23 could, if so desired, be eliminated.

Having thus shown and described one embodiment of the invention, it is evident that changes and modifications may be resorted to without departing from the spirit of the invention as contained in the appended claims.

What I claim and desire to cover by Let. Patents is:

1. In a cleansing machine, the combination of a fluid container, a stationary element into which the article to be cleansed may be placed, said element having a rotatable element rotatably attached thereto, and means for driving the rotatable element, both of said elements being removable together from said driving means and from within the container.

2. In a cleansing machine, the combination of a container, a movable fluid agitating element arranged in the container, a support for the agitating element removably arranged within the container, means for driving the agitating element, said agitating element being constructed to be connected and disconnected from the driving means upon the insertion and removal of the support from within the container, said support being open at an end and permitting articles to be cleansed to be arranged therein.

3. In a cleansing machine, the combination of a fluid container, a stationary receptacle into which articles to be cleansed are placed, said receptacle having dished elements to deflect the fluid towards the interior thereof, a rotatable element arranged between the container and the stationary receptacle and being rotatable around the deflecting elements of the receptacle, said rotatable element being constructed to direct the fluid towards the receptacle and cooperating with the deflecting elements of the receptacle to direct the fluid towards the center of the container.

4. In a cleansing machine, the combination of a fluid container, a stationary element constructed to receive the articles to be cleansed arranged within the container, said element having means separated from each other and extending into the container for directing the fluid towards the articles to be cleansed, a rotatable element rotatable around the stationary element and said

means operable to agitate the fluid and co-operating with said means to direct the fluid towards articles to be cleansed.

5. In a cleansing machine, the combination of a fluid container, a stationary element removably arranged within the container for the reception of articles to be cleansed, a fluid agitating element operable to direct the fluid towards the articles to be cleansed, and means for driving the agitating element, said stationary element and agitating element being constructed to be connected and disconnected as a unit from the driving means upon their insertion and removal from the fluid container.

- 10 6. In a cleansing machine, the combination of a fluid container, a stationary element with which the articles to be cleansed may be placed, said element including a plurality of separated fluid deflecting arms having a guard extending between the same, and a rotatable fluid agitating means co-operating with said arms to direct the fluid towards the articles to be cleansed.

- 15 7. In a cleansing machine, the combination of a fluid container, a stationary element arranged within the container, an element into which the articles to be cleansed are placed removably arranged within the stationary element, said stationary element having means to direct the fluid towards the second mentioned element and a rotatable member arranged to direct the fluid towards the element containing the articles to be cleansed, the rotatable element being rotatable about said means, said means and rotatable member cooperating to direct the fluid towards the second mentioned element.

- 20 8. In a cleansing machine the combination of a fluid container, a stationary element arranged within and spaced apart from the fluid container, said last mentioned element being removably arranged within the container and having ribs which are provided with a concave deflecting surface to direct the fluid towards the center of the container, and a rotatable member arranged between the container and the stationary element adapted to rotate around said ribs, said ribs and rotatable member cooperating to direct the fluid towards the center of the container.

- 25 9. In a cleansing machine, the combination of a fluid container, a stationary element into which the articles to be cleansed may be placed, consisting of a ring arranged to engage the container, the under side of said ring having a deflecting surface to deflect the fluid towards the stationary element and having a plurality of separated arms also having a deflecting surface, a guard secured to and extending between said arms and a rotatable member arranged between the container and said arms.

- 30 10. In a cleansing machine, the combina-

tion of a fluid container, a stationary element constructed to receive the articles to be cleansed, and a rotatable element, said stationary element and rotatable element having radial and upwardly extending members cooperating with each other to direct the fluid towards the interior of said stationary element.

35 11. In a cleansing machine, the combination of a container, a rotatable member having a pair of blades rotatable within the container, means for rotating said member, a member having a plurality of ribs arranged to direct the cleansing fluid towards the center of the container, a removable basket arranged within the member having said ribs, and means whereby said member having said blades and the member having ribs may be removed from the container and the driving means as a unit.

40 12. In a cleansing machine, the combination of a container, a member removably arranged in the container and having a plurality of ribs arranged to direct the cleansing fluid towards the center of the container, a rotatable blade, means for rotating said blade and means whereby said blade may be removed from the means for rotating the same upon the removal of the member having said ribs.

45 13. In a cleansing machine, the combination of a container, a member into which the articles to be cleansed are placed, a fluid agitating element suspended from an end of said member below said member and means for actuating said agitating element.

50 14. In a cleansing machine, the combination of a fluid container, a stationary element into which the articles to be cleansed may be placed, said element including a plurality of separated arms, a guard extending between the separated arms and rotatable fluid agitating means rotatable around said arms.

55 15. In a cleansing machine, the combination of a container, a removable fluid agitating element arranged in the container, a support for the agitating element removably arranged with respect to the container, said agitating element being separable from the support and arranged between an end of the support and the container, and means for driving the agitating element, said agitating element being constructed to be cooperatively connected and disconnected from the driving means upon the insertion and removal of the support from within the container.

60 16. In a cleansing machine, the combination of a container, an element into which articles to be cleansed may be arranged, said element being removably arranged in the container, and having radially arranged curved members to direct the fluid towards the articles to be cleansed and curved fluid

agitating means rotatably mounted adjacent said curved members to cooperate with the curved members of the first mentioned element.

5. 17. In a cleansing machine, the combination of a fluid container, a stationary receptacle constructed to receive the articles to be cleansed, said receptacle being removably arranged within the container, a driven ro-

tatable element removably connected to the 10 receptacle and removable from the container with the receptacle, driving means for the rotatable element, said rotatable element being removable from the driving means.

In witness whereof, I hereunto subscribe 15 my name this 21st day of February, A. D. 1919.

WILLIAM H. DUNN.
